UNITED STATES PATENT OFFICE

169,377

DRINKING MUG

Edward W. Kover, Sherman Oaks, Calif.

Application November 14, 1952, Serial No. 22,282

Term of patent 14 years

(Cl. D44—9)

To all whom it may concern:

Be it known that I, Edward W. Kover, a citizen of the United States, residing at 14649 Ventura Boulevard, Sherman Oaks, in the county of Los Angeles and State of California, have invented a new, original, and ornamental Design for a Drinking Mug, of which the following is a specification, reference being had to the accompanying drawing, forming a part thereof:

Fig. 1 is a front perspective view of a mug embodying my improved design;

Fig. 2 is a rear elevational view thereof;

Fig. 3 is a plan view of the same;

Fig. 4 is an inverted plan view of the same; and

Fig. 5 is a side elevational view of the same. The dominant features of my design reside in the portions shown in full lines.

I claim:

The ornamental design for a drinking mug, as shown and described.

EDW. W. KOVER.
